FLASHLIGHT

Herman G. Graubner, New York, N. Y.

Application June 14, 1954, Serial No. 30,989

Term of patent 14 years

(Cl. D48—24)

Fig. 1.

Fig. 2.

*Fig. 3.**Fig. 4.**To all whom it may concern:*

Be it known that I, Herman G. Graubner, a citizen of the United States of America, residing at New York, in the county of New York and State of New York, have invented a new, original, and ornamental Design for a Flashlight, of which the following is a specification, reference being had to the accompanying drawing, forming part hereof.

In the drawing:

Fig. 1 is a top elevational view of a flashlight showing my new design;

Fig. 2 is a side elevational view thereof;

Fig. 3 is a front end elevational view; and

Fig. 4 is a rear elevational view.

The central portion of the casing of the flashlight is of indeterminate length.

I claim:

The ornamental design for a flashlight, substantially as shown and described.
